UNITED STATES PATENT OFFICE

MAX KRISIEP, OF WYOMISSING, PENNSYLVANIA, ASSIGNOR TO TEXTILE MACHINE WORKS, OF WYOMISSING, PENNSYLVANIA, A CORPORATION OF PENNSYLVANIA

BRAIDING CARRIER

Application filed November 12, 1929. Serial No. 406,565.

This invention relates to yarn carriers for braiding machines, and the like.

Ordinarily, carriers of the type to which my invention relates, comprise a mounting or base member, a spindle thereon for the cop or bobbin, a weight or spring actuated tension and take-up device for automatically taking up the yarn which is slackened due to the sinuous path of travel of the carrier, and a machine-stop tripping device, which operates to stop the machine, when the yarn breaks.

Under operating conditions, these carriers are generally subjected to constant and comparatively severe jarring strains, while their yarn-feed controlling mechanism is required to respond to sudden and impulsive adjustments; such conditions heretofore causing excessive breakage of the yarn and parts of the carriers.

The primary object of my invention is to provide an improved yarn carrier, which overcomes the deficiencies mentioned, and which embodies sensitive and quick acting yarn-feed controlling means, accomplishing smooth and efficient yarn-feeding action; and novel bobbin mounting means, facilitating the application and removal of bobbins, and preventing axial movement of the same during operation.

The invention comprises the novel elements, features of construction, and arrangement of parts in operative relationship, for attaining the above and other objects, as herein exemplified by a preferred embodiment, while its scope is more particularly indicated in the appended claim.

Further objects and attendant advantages of the invention, will become more readily apparent from the following detailed description, reference being had to the accompanying drawings in which—

Fig. 1 is a front elevational view of my improved yarn carrier, having a bobbin applied thereto, and the yarn threaded in readiness for operation.

Fig. 2 is a central elevational sectional view, partly in full, and substantially taken as indicated by the arrows 2—2 on Fig. 1,

the bobbin and thread being diagrammatically indicated in dot-and-dash lines.

Fig. 3 is a plan view of the carrier shown in Fig. 2, and more particularly discloses the mechanism for releasing the bobbin ratchet-element to permit the bobbin to rotate when the proper tension is applied to the yarn.

Fig. 4 is a side elevational view of the carrier, as it appears before a bobbin is mounted thereon.

Fig. 5 is a side elevational view of a detachable ratchet-element, which is inserted in the top of a bobbin and serves as a means for controlling the rotation of the same.

In the embodiment shown in the accompanying drawings, the carrier essentially comprises a base member 11; a fixed rod or spindle 12; a bobbin holder or sleeve 13, on which a yarn cop, or bobbin 14 is mounted, and which is adapted to freely rotate on the spindle 12; a bobbin ratchet-element 15 detachably secured to the bobbin 14 and adapted to assist in controlling its rotation; and a tubular standard or post 16, which carries a common machine-stop tripping element 17, 75 yarn tensioning and take-up means as hereinafter fully described, and a spring pressed pawl or ratchet-element controlling device 19.

The base member 11 comprises spaced top and bottom plates 21 and 22, a connecting web or heart-piece 23 and a bottom stud 20. These parts are shaped to adapt the base to the particular type of braiding machine, or the like, with which the carrier of my invention is to be employed, and may be integrally formed, as shown, or separately constructed.

Integral with the top plate 21, are two studs or bosses 24 and 25, which are connected with each other and the plate 21 by a strengthening web 26.

The rod or spindle 12, is fixed in a central bore of the boss 24, while the tubular post or standard 16 is firmly secured to the stud 25, preferably by welding.

In the present instance, the tubular standard 16 is of elliptical cross-section, open at its top and along its front as at 27, as far as the stud 25, and conveniently accommodates and guides the yarn tensioning and take-up device, consisting of a tubular slide member 28, 100

of similar cross-section as the standard and having a cam or wedge-shaped upper end 29, and provided with a hook-shaped yarn guide 31 at its lower end; a tension spring 30 connecting the slide member 28 with the machine-stop tripping element 17. Instead of the hollow standard 16, other types of conventional posts or supports can be utilized to guide the slide member 28, and carry the parts just described.

The ratchet-element controlling device 19, is mounted on the upper end of the standard 16, and consists of a fixed bearing 32, in which a detent or releasing member 33 is pivoted and held in cooperative engagement with the ratchet-element or wheel 15 by a spiral spring 34. A depending extension 35 of detent 33, extends into the upper open end of the standard 16, where it is engaged by the upper cam or wedge-shaped end 29 of the slide member 28, and is thereby moved laterally an amount sufficient to disengage the detent 33 from the ratchet wheel 15, as indicated in dot-and-dash lines in Figs. 2 and 3.

The machine-stop tripping element 17 comprises two arcuate plates 17a and 17b riveted or otherwise joined together as at 17c and shaped in their center to encompass the standard 16, with sufficient clearance to permit the same to freely slide vertically along the standard between the web 26 and a stop 36 formed or secured on the standard.

Suitable yarn guides 37 and 38 are fixed to the standard 16. The yarn, normally passes from the bobbin 14, over hook-guide 37, under the similar guide 31 and through the guide 38, from where it goes directly to the braiding point, or other point of the machine to which the yarn is to be fed.

To mount the bobbin 14 for free rotation on the spindle 12, it is pushed down over the bobbin-holder or sleeve 13 which is provided with pressure springs 39 to engage the inner wall of the bobbin and hold it against axial and rotary motion on the same; a retaining collar 42 fixed on the spindle 12, keeping the bobbin holder 13 in the position shown.

By referring to Fig. 5, it will be noted that the ratchet-element 15, is fixed on the end of a sleeve 41, which is similar to the sleeve 13 and is also provided with springs 40 for firmly but removably connecting it with the bobbin 14.

Operation

After the bobbin 14 has been forced onto the holder 13 and the sleeve 41 forced into the bobbin top until the ratchet-element or wheel 15 registers with the detent 33, the yarn is threaded through the guides 37, 31 and 38, as shown, and the carrier is in readiness for operation. As the pull or tension on the yarn is increased, the slide member 28 will be moved vertically by the yarn, against the tension spring 30, whose lower end is connected

to the machine-stop tripping element 17, with consequent and simultaneous raising of the same to its upper or inoperative position against the stop 36. When the pull on the yarn is increased sufficiently to take up its slack, or until the upper end 29 of the slide member 28 engages with and moves the extension 35 laterally, the detent 33 will disengage the ratchet teeth of element 15 and permit the bobbin 14 to freely rotate on the spindle and feed its yarn until the pull on the latter decreases again, and permits spring 30 to pull slide member 28 out of engagement with the extension 35. Should the yarn break, the slide member 28 will immediately drop on the element 17, forcing the same to move down into its lower or operating position, as indicated in Fig. 2, where the projecting plates 17a 17b effect the stopping of the machine as usual.

It is to be noted, that due to the provision of the hollow slide member 28, a comparatively long spring 30 can be utilized for the tension and take-up device, thereby obtaining the proper resiliency and flexing action for smooth feeding and taking-up of the yarn; the enclosing of the spring in this manner also preventing catching of the yarn in the same, in case of breakage. The entire combination and coaction of the parts is reduced to a minimum of simplicity without sacrificing strength and rigidity of structure, which is essential in carriers of this type, for reasons already pointed out.

Of course, the yarn carrier shown and described, may be changed and modified in various ways, and changes may be required and desirable under certain conditions, it is therefore to be understood that the invention is not limited to the exact construction, shape and arrangement of elements disclosed, but that such changes and alterations may be made as fairly come within the scope of the invention herein set forth and more particularly pointed out in the appended claim.

I claim:

In a yarn carrier having a base member and a rotatable ratchet controlled bobbin; a parallel tubular standard; yarn tensioning means comprising; a pawl pivotally mounted on said standard for engaging and disengaging said bobbin, said pawl having an extension projecting into said tubular standard; a tubular thread-carried slide mounted in said standard and having an end portion adapted to engage said extension of said pawl to disengage the latter from said bobbin; a machine-stop device limitedly slideable on said standard; and a tensioning spring in said slide for connecting the latter to said stop device for normally maintaining said stop device in inactive position.

In testimony whereof I affix my signature.

MAX KRISSIEP.
